CLAIM

The ornamental design for a display screen with graphical user interface, as shown and described.

DESCRIPTION

FIG. 1 is a front view of a first embodiment of a display screen with graphical user interface, showing our new design; and,

FIG. 2 is a front view of a second embodiment of a display screen with graphical user interface, showing our new design.

The broken lines around the FIGS showing a display screen form no part of the claimed design. The broken lines within the FIGS show portions of the display screen with graphical user interface that form no part of the claimed design.

1 Claim, 2 Drawing Sheets
